ESCUCHEON

Jack H. Malek, Parsippany, and Raymond C. Turner,
Brooklyn, N.Y., assignors of one-third each to Harry
Greenwald and Louis Wolff

Filed July 6, 1965, Ser. No. 86,045

Term of patent 14 years

(Cl. D50—6)

FIG. 1 is a plan view of an escutcheon, showing our new design;

FIG. 2 is the reverse side thereof;

FIG. 3 is an edge view thereof; and

FIG. 4 is a sectional view thereof taken through lines 4—4 of FIG. 1.

The dominant features of the design reside in the solid line portions.

We claim:

The ornamental design for an escutcheon, substantially as shown and described.
